US0D1112322S

(12) **United States Design Patent** (10) **Patent No.:** **US D1,112,322 S**
Lindgren et al. (45) **Date of Patent:** **** Feb. 10, 2026**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Per J. Lindgren**, San Rafael, CA (US);
Nadaleen Frances Tempelman-Kluit,
San Jose, CA (US)

(73) Assignee: **Apple Inc.**, Cupertino, CA (US)

(***) Term: **15 Years**

(21) Appl. No.: **30/001,883**

(22) Filed: **Apr. 30, 2025**

(57) **CLAIM**

The ornamental design for a display screen or portion thereof with graphical user interface as shown and described.

DESCRIPTION

The file of this patent contains at least one figure executed in color. Copies of this patent in color will be provided by the Office upon request and payment of the necessary fee. FIG. 1 is a front view of a display screen or portion thereof with graphical user interface showing the claimed design; and,

FIG. 2 is a front view of a second embodiment thereof. The broken lines in the figures show a display screen or portion thereof, and form no part of the claimed design.
